DESIGN FOR A DISPLAY FORM FOR HABERDASHERY

Arthur E. Orloff, New York, N. Y.

Application August 15, 1939, Serial No. 86,691

Term of patent 3½ years

To all whom it may concern:

Be it known that I, Arthur E. Orloff, a citizen of the United States and a resident of New York, in the county of New York and State of New York, have invented a new, original, and ornamental Design for a Display Form for Haberdashery, of which the following is a specification, reference being had to the accompanying drawing, forming part thereof.

The figure is a perspective view of a display form for haberdashery showing my new design.

I claim:

The ornamental design for a display form for haberdashery, as shown.

ARTHUR E. ORLOFF.
